CLAIM

The ornamental design for data processing system peripheral equipment as shown and described.

DESCRIPTION

FIG. 1 is a top, front, left perspective view of data processing system peripheral equipment in accordance with our design; FIG. 2 is a bottom, rear, right perspective view thereof; FIG. 3 is a front elevational view thereof; FIG. 4 is a top plan view thereof; FIG. 5 is a left side elevational view thereof; FIG. 6 is a rear elevational view thereof; FIG. 7 is a bottom plan view thereof; and, FIG. 8 is a right side elevational view thereof. The broken lines represent portions of the data processing system peripheral equipment that form no part of the claimed design.
